* cited by examiner

Primary Examiner — Jennifer L Watkins(74) Attorney, Agent, or Firm — Fross, Zelnick, Lehrman & Zissu, P.C.; Charles T. J. Weigell, Esq.(57) CLAIM

The ornamental design for a shoe as shown and described.

DESCRIPTION

FIG. 1 is a front perspective view of the shoe showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depicting portions of the shoe sole show portions of the shoe that form no part of the claimed design. Broken lines other than those depicting the shoe sole represent the outline of a human leg or leg form on which the shoe is placed for illustrative purposes and form no part of the claimed design.
